UNITED STATES PATENT OFFICE.

CLAUDE W. GEIGER, OF DENVER, COLORADO.

HAND-OPERATED MEDICINAL POWDER MIXING AND GRINDING CYLINDER FOR DRUGGISTS' USE.

Application filed July 21, 1923. Serial No. 652,981.

To all whom it may concern:

Be it known that I, CLAUDE W. GEIGER, a citizen of the United States of America, residing at the city and county of Denver, and State of Colorado, have invented new and useful Hand-Operated Medicinal Powder Mixing and Grinding Cylinders for Druggists' Use, of which the following is a specification.

10 My invention relates to a hand operating medicinal powder mixing and grinding cylinder for the use of druggists and prescription filling and medicine making clerks.

And the objects of my invention are:

15 First: To provide a medicinal powder mixing and grinding hand operating cylinder that is adapted to quickly mix and grind medicinal powders used to fill prescriptions and other purchases.

20 Second: To provide a mixing and grinding hand grasping and manipulating cylinder, by means of which a druggist can mix different kinds of medicinal powders into medicines, and also for grinding a powder or powders to a much finer mesh than they naturally occur in, as desired.

I attain these objects by the mechanism illustrated in the accompanying drawings, in which:

30 Figure 1 is a perspective view of a hand operating powder mixing cylinder embodying my invention.

Fig. 2 is a longitudinal section through the center of the same, and

35 Fig. 3 illustrates a modification of the removable cap of the cylinder.

Similar letters refer to similar parts throughout the several views.

Referring to the drawings:

40 The numeral 1 designates a cylinder made of any suitable material, preferably a light weight material, like wood-fiber, celluloid, or hard rubber.

45 The cylinder represented in Figure 1 is a full size illustration of a size of cylinder best adapted to all around general use for mixing and grinding powders, but a smaller size and also a larger size can be used for special work. The cylinder is preferably

50 provided with an integral bottom 2, and the inner face of the cylinder wall is inwardly curved adjacent the bottom of the cylinder, in order to merge with the bottom, and thus eliminate an angular corner at

55 the bottom of the cylinder, as clearly shown

at 3. The cylinder is open at its upper end, and an annular shoulder 4 is formed on the inner face of the cylinder in the wall near the open end thereof, by reducing the thickness of the cylinder wall as 60 shown at 5, from its open end to the point where it is desired to form the said shoulder 4. The cylinder is normally closed by a cap or cover 6, the rim 7 of which is formed with an annular recess 8 which is 65 adapted to receive the reduced end portion 5 of the cylinder, the inner portion of the rim resting squarely upon the shoulder 4, as shown. The inner face of the rim 7 of the cap is curved to merge with the 70 flat end portion thereof, to eliminate an angular corner in the said cap, and when the cap is placed upon the cylinder, the cylinder presents an unbroken interior cylindrical surface, which merges at one end 75 into the bottom, and at the other end into the cap, thus eliminating angular corners at each end of the same, as will be understood by reference to Figure 2. Within the cylinder are placed two or more metal balls 9, preferably steel balls, and these balls have a smooth polished surface, and are of a size which will insure sufficient weight for the purpose intended. The radius of 80 the curve which merges the side wall and the end walls of the cylinder may be either the same or slightly greater than that of the balls which are used, in order that the balls when rolled in the cylinder may engage every part of the surface of the same. 85

In Figure 3 I have shown a slight modification in the arrangement of the open end of the cylinder and of the cap which fits over the same. In this arrangement the open end portion of the cylinder wall is reduced in thickness for a suitable distance, as shown at 10, to form a flat annular shoulder 11 in the outer surface of the said wall; and a cap 12 is employed, the annular portion of which is correspondingly reduced in 90 thickness to form an annular shoulder 13 which rests squarely on the rim of the cylinder, while the rim of the cap rests squarely upon the annular shoulder 11 of the cylinder. The end wall of this cap is also curved to merge into the cylinder wall, as in Figure 3, to avoid an angular corner. 95

In practice, the material to be mixed, ground or pulverized is placed in the cylinder and the cap is then placed thereon. 100

- 5 The ends of the cylinder are then grasped, and the cylinder is held so that its longitudinal axis is on a horizontal plane. The cylinder is then rapidly revolved in a generally circular path, so as to cause the balls to roll rapidly around the cylinder and over the material therein, which will result in quickly mixing and pulverizing the said material to the required degree of fineness.
- 10 It is understood that uniform angular movement of the cylinder in a definite orbit could not accomplish the object of the invention for the reason that the balls would not or at least not rapidly travel over the 15 surface of the cylinder. It is only by quick accelerations and retardations such as a person can carry out by intuition conscious of its effects, that the intended grinding action can be carried out. The relative motion of 20 the balls over the surface of the cylinder is indicated to the person through the vibrations communicated through the sense of touch and the absence of relative motion is indicated by the absence of such vibrations.
- 25 This is a matter of observation and experience with which most persons are familiar and which can be quickly acquired by prac-

tice. As there are no angular surfaces in the cylinder, the material to be mixed and pulverized is always subject to the action of 30 the balls, and the mixing and pulverizing action is therefore quickly and efficiently accomplished. The improved device is designed for the same purposes as the well known mortar and pestle commonly employed by druggists and chemists. 35

Having described my invention, what I claim as new and desire to secure by Letters Patent, is:

A method of mixing medicinal powders, 40 which consists in confining the ingredients to be mixed together with rolling bodies in a drum and moving the drum by hand at varying rates and in such directions as to impel by irregular centrifugal action the bodies 45 to rapidly roll over the inner surface of the drum.

In testimony whereof I affix my signature in presence of two witnesses.

CLAUDE W. GEIGER.
